UNITED STATES PATENT OFFICE.

FREDERIC SCHAEFER, OF PITTSBURGH, PENNSYLVANIA.

CONNECTING-BAR.

1,240,493.

Specification of Letters Patent. Patented Sept. 18, 1917.

Application filed July 7, 1914. Serial No. 849,550.

To all whom it may concern:

Be it known that I, FREDERIC SCHAEFER, a resident of Pittsburgh, in the county of Allegheny and State of Pennsylvania, have 5 invented a new and useful Improvement in Connecting-Bars, of which the following is a specification.

This invention relates to pressed metal connecting bars, such as are used for connecting the brake levers of railway trucks, or for other purposes, and to push rods for 10 brake cylinders, etc. The object of the invention is to provide a bar or rod of the kind described which is light yet very strong, 15 which can be readily adapted to all types and arrangements of brake rigging or other mechanism, which is reinforced against bending and tensile strains at all of the usual weak points, which gives an extended 20 bearing upon the pivot pin or pins to which it is connected, which is durable and is not likely to fail under service conditions, and which can be readily manufactured at low cost.

25 The invention comprises the bar or rod hereinafter described and claimed.

In the drawings, which represent several embodiments of the invention, Figure 1 is a top plan view of a connecting bar; Fig. 30 2 is a side elevation thereof; Figs. 3, 4 and 5 are cross sections on a larger scale taken respectively on the lines 3—3, 4—4, and 5—5, Fig. 2; Fig. 6 is a detail longitudinal section on the line 6—6, Fig. 2; Fig. 7 is a 35 view corresponding to Fig. 2 and showing a modified form of the invention; Figs. 8 and 9 are cross sections taken respectively on the lines 8—8, and 9—9, Fig. 7; Figs. 10 and 11 are views corresponding to Fig. 8 and 40 showing other modifications; Fig. 12 is a side elevation of a push rod embodying the invention; Fig. 13 is a plan view of one end thereof; and Fig. 14 is a detail view showing a modification.

45 The connecting bar shown in the drawings comprises a body portion 1 formed of pressed metal, preferably steel, and having a suitable hollow cross section. At each end said bar is slotted longitudinally, as at 2, to 50 provide pairs of oppositely disposed ears 3, which preferably are flat and parallel to each other, and are rounded at their outer ends, as shown at 4. The pairs of ears at opposite ends of the bar are provided with one or 55 a plurality of sets of oppositely disposed holes 5, for receiving pivot pins for con-

necting said bar to other parts. The metal surrounding each of said holes is displaced laterally, either inwardly toward the center line of the bar, or outwardly, as shown in Fig. 1, to form protuberances 6, which materially increase the bearing surface of each ear in contact with the pivot pin to which it is connected.

To strengthen the bar against bending strains, especially sidewise or in a direction parallel to the axes of the holes 5, and to reinforce it at the junction of the ears with the body portion of the bar, the metal of the side portions of said bar, opposite the roots of the slots 2, is also displaced laterally, as at 7, preferably in a manner to maintain the original thickness of the metal, which not only increases the beam effect and strengthens the bar against bending stresses in all directions, but also reinforces it against tensile stresses.

The connecting bar described is preferably made from a flat sheet or plate of forged or rolled steel, which is first slotted at its opposite ends to form the ears 3. Either simultaneously with the slotting operation, or subsequently thereto, each end of the blank is subjected to a forging or pressing operation in suitable dies, which operation punches the holes 5 and forces the metal of the ears outwardly and into the die to produce the protuberances 6, and also shapes the side enlargements 7 opposite the roots of the slots 2. The blank is then bent or folded on its central longitudinal line to the proper cross sectional shape, either the shape shown in Fig. 5 or any other suitable shape, such as shown in Figs. 8, 10 or 11. In some cases, when the end portions of the bar are bent upwardly, as shown in Fig. 2, it is desirable to press the side walls of the bar more closely together, to increase the depth of the body portion, which in the form shown in Figs. 1 and 2 is greater than the depth of the ears 3, and which bar is therefore materially reinforced against bending strains in the vertical plane, due in part to the greater depth than width of the section, as shown in Fig. 5. In other cases, when the bar is substantially straight from end to end, as shown in Fig. 7, the cross section may be round, as shown in Fig. 8, or square, as shown in Figs. 10 and 11, and which illustrate different positions of the diagonals of the square section with reference to the top of the bar. The sections shown in Figs. 8,

10 and 11 are particularly valuable as they are uniform about the central longitudinal axis of the bar and consequently the metal is distributed most advantageously and has maximum strength with a minimum amount of metal. In all cases the cross sectional shape to which the bar is folded depends upon its particular use and whether it is desired to reinforce the bar against strains in 10 the vertical or in the horizontal plane.

After the bar is folded in the manner described the openings 5, which lie directly opposite each other, are trued by a reaming operation so as to reduce wear on the pivot 15 pins.

The connecting bar described is simple and can be readily manufactured by ordinary machinery. It is very strong and durable for the amount of metal employed, is light 20 in weight, and is not liable to fail under even the most severe conditions encountered in service.

The invention may also be applied to push rods, such as are used in brake cylinders or 25 the like. As shown in Figs. 12 and 13, such rods are made by slotting a flat sheet or plate at one end to form the slots 10, whereupon the slotted blank is subjected to a die forging or pressing operation to form the 30 pivot apertures 11 and to force the metal outwardly around said apertures, as at 12, to increase the bearing surface, and to also force it outwardly opposite the root of the slot 10 to form the side swells 13. The 35 blank is then bent around a longitudinal axis to bring the ears 14 into parallelism and to form the tubular body 15, which may be provided with a suitable end plug or head 16, if desired. This is a very cheap and strong 40 push rod which can be made at very low cost and has maximum strength for the metal employed.

What I claim is:—

1. A bar, comprising a one-piece hollow body member slotted at its ends to form 45 pairs of oppositely disposed ears, the metal

of said body member opposite the roots of said slots being of substantially uniform thickness around the entire periphery of the body and being also displaced laterally into 50 arch form to increase the strength of the bar.

2. A connecting bar, comprising a one-piece hollow body member provided with slots at both ends to form pairs of parallel ears, said ears having oppositely disposed 55 apertures with the metal around said apertures thickened to thereby increase the bearing surface, and opposite the roots of said slots being of substantially uniform thickness around the entire periphery of the body 60 and being displaced outwardly into arch form to increase the strength of the bar.

3. A connecting bar, comprising a body member formed of plate metal bent to hollow form and slotted at both ends to form 65 pairs of parallel ears, said ears being narrower than the depth of said body member and being provided with oppositely disposed apertures with the metal around said apertures thickened to thereby increase the bearing 70 surface, and opposite the ends of said slots being of substantially uniform thickness around the entire periphery of the body and being displaced outwardly into arch form to increase the strength of the bar. 75

4. A bar or rod, comprising a hollow body having its end portion slotted to form a pair of parallel ears, said ears being provided with oppositely disposed apertures with the metal around said apertures thickened to 80 thereby increase the bearing surface, the metal of said body opposite the root of said slot being of substantially uniform thickness around the entire periphery of the body and being also displaced laterally into arch form 85 to increase the strength of the bar.

In testimony whereof, I have hereunto set my hand.

FREDERIC SCHAEFER.
